MACHINE FOR SHAPING UPPERS OVER
LASTS

Bernhardt Jorgensen, Marblehead, Mass., assignor to United Shoe Machinery Corporation, Borough of Flemington, N. J., a corporation of New Jersey

Application April 24, 1940, Serial No. 331,300

26 Claims. (Cl. 12—7)

This invention relates to machines for shaping uppers over lasts, and is herein illustrated as embodied in a lasting machine of the same general character as disclosed in United States Letters Patent No. 2,181,896, granted on December 5, 1939 on an application of mine. It is to be understood, however, that in various aspects the invention is not thus limited in its applicability.

The power-operated machine shown in the above-mentioned Letters Patent is provided with toe-lasting mechanism and with opposite side-lasting mechanisms, the latter acting at the ball portion of the shoe and cooperating with the toe-lasting mechanism to last the entire forepart of the shoe. The toe-lasting mechanism includes a toe clamp or gripper which is closed on the margin of the upper by a treadle prior to the starting of the power operation of the machine, and the side-lasting mechanisms include other grippers which are closed on the upper by a second depression of the same treadle after the operator has positioned the margin of the upper in proper relation to them. In the power operation of the machine the several grippers pull the upper in response to heightwise movement of the last, and thereafter the margin of the upper is wiped inwardly over an insole on the last, first at the sides of the ball portion and then around the toe portion of the shoe.

For purposes of the present invention the construction herein shown is such that the jaws of the grippers of the side-lasting mechanisms are closed on the margin of the upper by fluid-operated means controlled by the usual clutch-actuating member by means of which the operator starts the power operation of the machine. The operator is thus afforded the same opportunity as heretofore to arrange the margin of the upper in proper relation to the side-gripper jaws after closing the toe gripper on the upper, but is relieved of the necessity of closing those jaws, this being incidental to the starting of the machine. In addition to the saving of time and effort thus involved, the use of fluid-operated upper-gripping means is advantageous for the reason that regardless of their thickness the upper materials are gripped with a definitely predetermined pressure which can be readily varied by varying the pressure of the operating fluid. In the construction shown the operating fluid is delivered to the fluid-operated upper-gripping means by a continuously operated pump which is conveniently in constant communication with the upper-gripping means but is rendered ef-

fective to develop the necessary fluid pressure only in response to closing of a valve through which the fluid is normally circulated at substantially atmospheric pressure, this valve being closed by the movement of the above-mentioned clutch-actuating member. While these features of the invention, and also certain novel features of gripper construction including fluid-operated jaw-closing means, are herein illustrated as applied to means for pulling the upper at the opposite sides of the last in a machine organization of the character above outlined, it is to be understood that in various novel aspects the invention is more generally applicable to machines of different kinds which have means for gripping and pulling upper materials.

As a further feature, the invention provides novel means for pulling portions of the sides of an upper extending heelwardly of the ball line in such manner that the upper is subjected to strain not only heightwise of the last, but also lengthwise of the last toward its heel end, as is desirable for the proper shaping of the upper in those locations. In the machine herein shown the construction is such that the pulling of the upper heightwise of the last by the grippers of the previously mentioned opposite side-lasting mechanisms is effected in response to heightwise movement of the last in a direction which is substantially perpendicular to the bottom of the forepart of the last, and a pull toward the heel end of the last is effected by moving these grippers lengthwise of the last. As illustrated, such movement of the grippers results from movement of the work support with the last in the direction heightwise of the last.

The above and other features of the invention, including novel means for controlling the opposite side margins of the insole in the vicinity of the side-lasting mechanisms, and various novel details of construction and combinations of parts, will now be more particularly described with reference to the accompanying drawings and thereafter pointed out in the claims.

In the drawings,

Fig. 1 is a view in front elevation of the upper portion of a machine in which the invention is embodied;

Fig. 2 is a plan view of a portion of the structure, with parts in section on the line II—II of Fig. 1;

Fig. 3 is a plan view of the forepart-lasting means;

Fig. 4 shows a portion of the machine in ele-

vation as viewed from the right, with parts in section;

Fig. 5 is a left-hand end elevation of a portion of the machine, with parts in section;

Fig. 6 is a plan view of certain parts shown in Fig. 5;

Fig. 7 shows one of the side-lasting mechanisms partly in elevation, as viewed from the right, and partly in section;

Fig. 8 is a view similar to Fig. 7 showing both of the side-lasting mechanisms with the parts in the positions which they assume in pulling the upper;

Fig. 9 is a plan view of the insole holdown and parts associated therewith, illustrating the relation of the holdown to the insole; and

Fig. 10 shows a portion of the insole holdown in front elevation, further illustrating its relation to the insole.

As in prior machines of the illustrated type, the shoe and last are positioned on a toe rest 2 which is movable downwardly with them against the resistance of a spring 4 (Fig. 8), and on a heel-end support 6 also movable downwardly with them against the resistance of a spring 8 along guideways 10 (Fig. 2) in the frame 12. The support 6 carries a pin 14 arranged to enter the spindle hole in the heel end of the last, the pin being mounted on a holder 16 vertically adjustable relatively to the support 6. For a reason herein-after explained the construction shown is such that the pin 14 is inclined in a direction lengthwise of the shoe, instead of being vertical as heretofore. As fully disclosed in Letters Patent No. 2,181,896, the shoe is clamped about its heel end by a heel band 18 carried by the vertically movable support 6, this heel band being moved lengthwise of the shoe into clamping relation thereto prior to the starting of the power operation of the machine by spring-operated mechanism which is released in response to movement of a plunger 20 (Fig. 4).

For lasting the toe end of the shoe the machine is provided with mechanism substantially like that disclosed in the above-mentioned Letters Patent. This mechanism comprises a toe former or band 22 arranged to engage the upper around the toe and to some extent also heelwardly of the toe portion and to wipe it heightwise of the last toward the edge of the insole in response to downward movement of the last and shoe, and wipers 24 (Fig. 3) for wiping the margin of the upper around the toe inwardly over the insole, these wipers being of such lengths as to overlap also substantial portions of the bottom of the shoe extending heelwardly of its toe portion. The band and the wipers are supported by a casting 26 (Fig. 1) which in the construction herein shown, while adjustable lengthwise of the shoe as heretofore, is not adjustable as heretofore about an axis extending widthwise of the shoe, but on the contrary positions the wipers 24 permanently in a horizontal plane. This eliminates any necessity for tipping the side-lasting mechanisms (hereinafter described) to maintain them in proper relation to the toe wipers and thus contributes to a better design of the operating mechanism than in the earlier construction. In order to position the bottom of the forepart of the shoe in proper relation to the horizontal toe wipers, the last pin 14 is necessarily positioned somewhat lower than heretofore relatively to the support 6 and is inclined in the manner above described. The toe wipers are advanced lengthwise of the shoe and are closed laterally of the shoe by mech-

anism operated by a rockshaft 28 (Fig. 3) which is operated by a cam (not shown) mounted on a cam shaft 30 (Fig. 4). The wipers are maintained in a heated condition by an electrical heating unit 32 (Fig. 3) mounted in a cover plate 34 on the casting 26.

Included also in the toe-lasting mechanism is means substantially like that shown in Letters Patent No. 2,181,896 for gripping the margin of the toe end of the upper prior to the starting of the power operation of the machine, so that in response to the downward movement of the last a pull heightwise of the last is applied to the upper as it is wiped upwardly by the toe band 22. This upper-gripping means comprises a pair of jaws 36 and 38 (Fig. 3), the jaw 36 being movable downwardly toward the jaw 38 to grip the upper by mechanism operated by the swinging of a lever 40 (Fig. 1) which is operated through a flexible cable 42 by a treadle (not shown). A latch 44 carried by the lever 40 is arranged to swing over a lug 46 to lock the jaw 36 in upper-gripping position, the lug 46 being mounted to turn with the wiper-operating rockshaft 28 so that the lever 40 is released to permit the release of the upper by the gripper substantially at the time when the toe wipers begin to wipe the margin of the upper over the insole.

Downward movement of the shoe is effected in the power operation of the machine by a toe presser foot 48 and a heel presser foot 50 arranged, respectively, to engage the toe and heel ends of the insole. The toe presser foot is supported by an arm 52 carried by vertically aligned rods 54 and 56 which are mounted for vertical movements and for turning movements in bearings in the frame. The arm 52 occupies initially a position in which the toe presser foot 48 is retracted rearwardly from over the shoe bottom, and the operator swings the arm forwardly to carry the presser foot into position over the shoe by means of a handle 58. Such forward swinging movement of the arm 52 serves to start the power operation of the machine. For this purpose, as more fully disclosed in Letters Patent No. 1,843,232, granted on February 2, 1932 on an application of mine, there is provided a rod 60 (Fig. 5) which is moved lengthwise in a rearward direction by the turning of the rod 56 and serves by that movement to swing a bell-crank lever 62 and thus to lift a link 64 connected to this lever. The link 64 is provided on its lower end with a hook 66 which in response to the upward movement of the link acts on a clutch-tripping arm 68 to trip or release a clutch 70 through which the cam shaft 30 is operated. Immediately after the starting of the power operation of the machine the toe presser foot 48 is carried downwardly into engagement with the insole and is further operated to depress the toe end of the shoe, the heel presser foot 50 being operated simultaneously to depress the heel end of the shoe. Substantially as disclosed in Letters Patent No. 2,181,896, the heel presser foot is vertically adjustable in a carrier 12 which is fast on a rod 74 mounted for vertical movements and for turning movements in the frame, the carrier being swung by the turning of the rod to carry the presser foot 50 into position over the heel end of the shoe and being moved downwardly by the rod to cause the presser foot to depress the shoe.

The machine is further provided with a pair of opposite side-lasting mechanisms, designated generally by the reference characters 76 (Fig. 3),

for pulling the upper and for wiping its margin inwardly over the insole at the sides of the forepart heelwardly of the toe portion of the shoe, so that the entire forepart of the shoe is lasted by the machine. These mechanisms are in many respects similar to corresponding mechanisms shown in Letters Patent No. 2,181,896, but differ therefrom in other respects. In the construction herein shown the two side-lasting mechanisms are supported by a casting 78 (Figs. 1 and 4) common to both of them, this casting having at its lower end a front pair and a rear pair of hub portions 80, 82 fast on rods 84 which are movable lengthwise of the shoe in bearings in the frame of the machine for a purpose hereinafter explained, the hub portions 80 and 82 of each pair being spaced from each other along the corresponding rod 84. Each side-lasting mechanism comprises a gripper designated generally by the reference character 86 for gripping and pulling the upper and a wiper 88 for wiping the margin of the upper inwardly over the insole, these parts being supported as hereinafter described on a carrier 90 which is movable toward and from the shoe along guideways 92 (Figs. 1 and 7) formed in opposite sides of a holder 94. In the construction shown each holder 94 has a depending stem 96 mounted in a split bearing in the casting 78, so that the side-lasting mechanisms may be adjusted independently of each other about axes extending heightwise of the shoe. After any such adjustment either mechanism is secured in adjusted position by a screw 98 acting on the split bearing. Each holder 90 and its guideways 92 are curved about an axis extending heightwise of the shoe, so that in its movement inwardly toward the shoe each side-lasting mechanism has a component of movement lengthwise of the shoe toward the toe end of the latter.

Initially the two carriers 90 are retracted as illustrated in Fig. 3 to provide ample room for the mounting of the shoe and last on the toe rest 2 and the heel pin 14, and they are moved inwardly to positions determined by the shoe prior to the starting of the power operation of the machine. Such inward movement of each carrier is limited by engagement of the shoe with a clamp member or bumper 100 (Fig. 8) mounted on a plate 102 secured to the carrier 90. The bumper may turn about a pin 103 on the plate to adjust itself to the shoe. Each carrier 90 is moved inwardly toward the shoe by a lever 104 (Fig. 4) pivotally mounted between its upper and lower ends on a pin 106 fast in the casting 78, the upper end of the lever being connected to the carrier by a link 108, as more particularly hereinafter described. In the construction herein shown the lower end of each lever 104 is connected by a link 110 to one arm 112 of a bell-crank lever 114 mounted to turn about one of the rods 84 between the spaced hub portions 80, 82 of the casting 78. The other arms 116 of the bell-crank levers 114 are pivotally connected to the outer ends of toggle links 118 the inner ends of which are pivotally connected together by a rod 120 on which is mounted a depending link 122. This link comprises arms 124 and 126 (Figs. 1 and 4) mounted respectively on the opposite ends of the rod 120 and connected together below the rod by a web 128. The upper end of the arm 124 of the link carries a roll 130 which is mounted between two guiding lugs 132 on the frame of the machine to assist in controlling the toggle links 118 in such manner that the side-

lasting mechanisms will be moved toward and from the shoe in unison. At its lower end the link 122 is pivotally connected to the front end of a lever 134 the rear end of which is fast on a rockshaft 136 supported in bearings in the frame. In the construction shown the side-lasting mechanisms are moved inwardly toward the shoe by springs 138 connected to the casting 78 and to the arms 112 of the bell-crank levers 114. Initially, however, they are held in retracted positions by a retaining lever 140 arranged to underlie the front end of the lever 134, as illustrated in Fig. 4. The lever 140 is swung to release the lever 134 and thus to permit the springs 138 to move the side-lasting mechanisms toward the shoe by movement of the plunger 20 hereinabove referred to as means for releasing the heel band 18 to cause it to be moved into clamping relation to the shoe. The construction is such that the lever 134 is released, as heretofore, only in response to further movement of the plunger 20 after the release of the heel band. For this purpose, as disclosed in Letters Patent No. 2,181,896, a rod 142 operated by the plunger is spaced initially from the lever 140 and acts thereon only after the release of the heel band. The movement of the lever 140 by the plunger is effected against the resistance of a spring 144 which is connected to the lower end of the lever and holds it initially in a position determined by its engagement with a stop screw 146.

Each wiper 88, substantially as disclosed in the last-mentioned Letters Patent, consists of a resilient plate carried by a slide 148 (Figs. 4 and 7) curved similarly to the carrier 90 and mounted in correspondingly curved guideways 150 in the carrier to move relatively to the carrier widthwise of the shoe in a path curved similarly to the path of movement of the carrier, so that the wiper will have a component of movement lengthwise of the shoe toward its toe end as it is moved inwardly over the insole. The resilient wiper 88 may be sprung heightwise of the shoe as in the earlier construction by screws 152, one of which is shown in Fig. 7, to conform better to the contour of the shoe bottom. In the construction herein shown the wiper is not mounted directly on the slide 148, but on a plate 154 detachably secured by a pin 156 to the slide and in which the screws 152 are threaded. The outer ends of the two slides 148 are connected to the levers 104 by the previously mentioned links 108 which have ball-shaped outer ends engaging the levers and are pivotally mounted on pins 158 on the slides. When the levers 104, however, are operated by the springs 138 in the manner hereinbefore described, upon the release of the lever 134, the slides 148 are prevented from moving relatively to the carriers 90 by springs 160 connected to pins 162 on the carriers and to the pins 156 on the slides, these springs normally holding the slides in positions determined by engagement of shoulders 164 on the plates 154 (Fig. 4) with the inner end faces of the carriers. Accordingly, the carriers 90 and the parts thereon are moved inwardly toward the shoe by the levers 104 to positions determined by engagement of the bumpers 100 with the shoe. At the proper time in the cycle of operations of the machine further movements of the levers 104 serve to move the slides 148 relatively to the carriers 90 against the resistance of the springs 160 to cause the wipers 88 to wipe the margin of the upper inwardly over the insole. The levers 104 are operated for this purpose by further downward

swinging movement of the lever 134 which is effected by a path cam 166 (Fig. 4) formed in a cam wheel 168 fast on the shaft 30, substantially as disclosed in Letters Patent No. 2,181,896. This cam engages a roll 170 mounted on a lever 172 which is connected to the lever 134 by a link 174. The path cam 166 is enlarged at 176 to permit such downward movement of the lever 172 as occurs when the lever 134 is released by the movement of the plunger 20.

In accordance with the present invention, the construction is such that the jaws of the grippers 86, instead of being closed on the upper by an additional movement of the same treadle which operates the toe-gripper jaw 36 as in the earlier construction, are closed and held closed by fluid-pressure means. Each gripper includes a cylinder 178 pivotally mounted on a horizontal pin 180 supported in ears 182 extending upwardly from the carrier 90. Fast on the cylinder is a bracket 184 (Fig. 7), and detachably secured in fixed relation to this bracket by a pin 186 is a jaw 188 against which the upper is gripped by another jaw 190 pivotally mounted on the pin 186. Slidably mounted in the cylinder 178 is a piston 192, and pivotally connected to this piston is one end of a rod 194 which extends through a forked upwardly extending portion 196 of the bracket 184 and is pivotally connected at its other end to the jaw 190. A spring 198 mounted between the piston and the forked portion 196 of the bracket tends to move the piston in the direction to swing the jaw 190 away from the jaw 188. The piston is moved in the opposite direction to close the jaw 190 on the upper by pressure of fluid admitted to the cylinder 178. Formed in a head 200 fast on the cylinder is a passage 202 leading into the cylinder from a flexible tube 204 which is coupled to the cylinder head. As shown in Fig. 4, one of the tubes 204 is connected directly at its lower end to a T-shaped coupling 206, and the other tube is connected to a pipe 208 leading into this T-shaped coupling. Leading from the coupling 206, and communicating, therefore, with both tubes 204, is a flexible tube 210 connected at its lower end to a source of fluid supply. This source of fluid supply (Fig. 5) comprises a rotary pump 212 driven continuously through a belt 214 by the power shaft 216 of the machine, the pump being mounted within a reservoir or tank 218 which contains a body of liquid 220, preferably oil, under atmospheric pressure. Oil is admitted to the pump through a pipe 222 and is delivered by the pump to a coupling 224 one end of which communicates through piping 226 with the lower end of the flexible tube 210. The coupling 224 also communicates through piping 228 (Fig. 6) with a rotary valve 230 through which, when open, the oil is permitted to flow from the pump to a pipe 232 leading back to the tank 218. When the valve 230 is open, therefore, the pump merely circulates oil in the tank at substantially atmospheric pressure. The coupling 224 also communicates with a passageway 234 controlled by a valve 236. A spring 238 tends to force the valve 236 against its seat and thus to close the passageway 234, the amount of compression of this spring being adjustable by a screw 240. A pipe 242 leads from the valve 236 back to the tank 218. When the valve 230 is open as above described, the valve 236 is held by the spring in closed position. If the valve 230 is closed, however, the valve 236 is opened by the pressure of the oil against it to permit return of the oil to

the tank through the pipe 242, the amount of pressure maintained at this time being determined by the force of the spring 238 and being sufficient to operate the pistons 192 and close the jaws of the grippers 86 on the upper with the force necessary to hold the upper as the pull is applied thereto.

It will thus be seen that the gripping of the upper by the grippers 86 results from the closing of the valve 230. The valve is closed by a lever 244 extending therefrom and connected to mechanism which is operated by the forward swinging movement of the toe presser-foot arm 52 (Fig. 1), so that the closing of the grippers 86 10 as well as the tripping of the clutch 70 results from the movement of this arm without any special attention on the part of the operator. As already described, the swinging of the arm 52 imparts lengthwise rearward movement to the rod 60 (Fig. 5) which operates the bell-crank lever 62 to lift the clutch-tripping link 64. The bell-crank lever 62 is fast on a rockshaft 246 mounted in a bracket 248 on the rear of the frame of the machine, and fastened also to this rockshaft 25 by a key 250 is an arm 252 having a forked portion through which extends a bar 254. A plate 256 fast on the arm 252 is arranged to bear upwardly against a shoulder 258 on the bar 254, so that upward movement is imparted to the bar 254 by the swinging of the arm 252 as the bell-crank lever 62 is operated to trip the clutch. Extending downwardly from the bar 254 is a rod 260 the lower end portion of which is slidably mounted in a yoke member 262 and has fast thereon a collar 264 between which and a shoulder on the yoke member is a spring 266. The yoke member 262 is pivotally connected at its lower end to the lever 244 on the valve 230. Accordingly, the above-described upward movement 30 of the bar 254 serves to swing the lever 244 upwardly and thus to close the valve 230. The yoke member 262 extends downwardly through an opening in a cover plate 268 on the tank 218, and the upward swinging movement of the lever 244 is limited by its engagement with a shoulder 270 on the cover plate in this opening. It will be understood that any further upward movement of the bar 254 thereafter serves merely to compress the spring 266. 35 The grippers 86 are caused to open and release the upper in response to opening of the valve 230 substantially at the time when the wipers 88 begin to wipe the margin of the upper inwardly over the insole. The valve is thus opened by the 40 action of a spring 272 on the bar 254 when the bar is pushed rearwardly, i. e., toward the left as viewed in Fig. 5, to disengage its shoulder 258 from the plate 256, the opening movement of the valve being limited by engagement of a 45 screw 274 carried by the yoke member 262 with the cover plate 268. For thus pushing the bar rearwardly there is pivotally mounted on a stud 276 on the arm 252 a lever 278 which carries a pivoted finger 280 held by a spring 282 yieldingly 50 in engagement with the top of the forked portion of the arm 252. Threaded in a pin 284 which is mounted to turn in a forked portion of the lever 278 is a rod 286 slidably mounted at its lower end in a yoke member 288 pivotally connected to a lever 290 fast on the previously mentioned rock shaft 136 on which the lever 134 (Fig. 4) is mounted. Fast on the rod 286 in an opening in the yoke member 288 is a collar 292 between the lower end of which and a shoulder on the 55 yoke member is a compression spring 294. It 60 65 70 75

will thus be seen that when the yoke member 288 is moved upwardly by the lever 290 it acts through the spring 294 on the rod 286 to swing the lever 278 in the direction to cause the finger 280 to disengage the bar 254 from the plate 256. The lever 290 is thus operated by the lever 134 when the latter is moved by the cam 166 to force the wipers 88 inwardly over the shoe bottom. The finger 280 is spaced far enough initially from the bar 254 to prevent it from acting on the bar in response to that downward movement of the lever 134 which occurs upon its release by the lever 140 prior to the starting of the machine. The position of the finger relatively to the bar may be varied by turning the rod 286 by means of a head 296 on its upper end.

When the pull is applied to the upper by the grippers 86 in response to the downward movement of the last, the grippers may swing about the pins 180 in response to the force of the pull of the upper thereon against the resistance of springs 298. These springs surround rods 300 which are fast in the carriers 90 and extend upwardly through forked extensions 302 of the cylinder heads 200. The springs bear at their lower ends on these forked extensions and at their upper ends on nuts 304 threaded on the rods, lock nuts 306 being provided to hold the nuts 304 in adjusted positions.

The best results in the lasting of the shoe require that the upper extending heelwardly of the ball line be pulled somewhat in a heelward direction as it is pulled heightwise of the last. Accordingly, since the machine herein shown is so constructed that the bottom of the forepart of the shoe is substantially horizontal instead of being inclined downwardly toward the end of the toe as heretofore, the machine is provided with means for imparting to the side-lasting mechanisms including the grippers 86 bodily movement in a heelward direction in the course of the downward movement of the last. As previously explained, the casting 78 on which the side-lasting mechanisms are mounted is fast on a pair of rods 84 which are movable lengthwise of the shoe in bearings in the frame. One of these rods has fastened to its right-hand end a block 308 (Fig. 2) connected by a link 310 to one arm 312 (Fig. 1) of a bell-crank lever 314 mounted for swinging movement on the frame, and connected to the other arm 316 of this bell-crank lever is a spring 318 which tends to swing the lever in a counterclockwise direction and thus to move the casting 78 and the side-lasting mechanisms toward the toe end of the shoe. Initially the casting is held by the spring in a position determined as hereinafter described. The casting 78 and the side-lasting mechanisms are moved toward the heel end of the shoe against the resistance of the spring 318 in response to the downward movement of the heel-end support 6. Mounted to swing about a rod 322 carried by the heel-end support is a bell-crank lever 324 having a forked upwardly extending arm 326 which carries a trunnion block 328, and threaded in this trunnion block is a rod 330 which is rotatable in a bearing formed in a bracket 332. Rotatable in a bearing in the block 308 and also in the bracket 332 is a rod 334 connected by beveled gears 336 to the rod 330. The bracket 332 is thus supported on the rod 334, and mounted also on this rod is one end of the previously mentioned link 310. The bell-crank lever 324 has a second arm 338 which, as shown in Fig. 1, is positioned over a shoulder 340 on the frame 12. Accord-

ingly, when the heel-end support 6 is moved downwardly with the shoe the shoulder 340 acts on the arm 338 to swing the bell-crank lever 324 in a clockwise direction and thus 5 through the rods 330 and 334 to move the rods 84 and the casting 78 toward the heel end of the shoe. Movement of the rods 84 and the casting in the opposite direction under the influence of the spring 318 is limited by a rod 342 which is 10 threaded in a lug 344 on the arm 326 of the bell-crank lever 324 and is arranged to abut at one end against a web 346 on the heel-end support 6. Fast on the rod 334 is a hand wheel 348, and by turning this hand wheel the rod 330 may be turned relatively to the threaded trunnion block 328 to adjust the rods 84 and the casting 78 lengthwise of the shoe. The amount of upper-pulling movement toward the heel end of the shoe imparted to the side-lasting mechanisms may be varied by turning the rod 342 by means of a hand wheel 350 thereon. It will be evident that the turning of this rod adjusts the bell-crank lever 324 to space its arm 338 initially more or less above the shoulder 340, and it will be further evident that whenever such an adjustment of the bell-crank lever is 15 made a compensating adjustment of the rods 84 must also be made by turning the hand wheel 348 if the positions of the side-lasting mechanisms lengthwise of the shoe are to remain the same.

In order to insure that when the wipers 88 of the side-lasting mechanisms wipe the margin of the upper inwardly over the insole the portions of the margin of the insole over which these wipers operate will be held close against the bottom of the last, the machine is further provided with insole holdown mechanism shown in Figs. 1, 9 and 10, this mechanism being supported 20 by the carrier 72 which carries the heel presser foot 50 as hereinbefore described. Mounted to swing about a horizontal rod 362 on this carrier 25 35 are the hub 354 of an arm 356 on which is mounted a block 358. Pivotally mounted on pins 360 on this block for swinging movements laterally of the shoe about axes extending heightwise of the shoe are two arms 362 which carry holdown members 364 arranged to engage the insole near its marginal edge in the paths of the inward movements of the wipers 88. By reason of the 30 shape of the arms 362 the members 364 extend in generally parallel relation to the portions of the edge of the insole which curve inward heelwardly of the ball line. The members 364 are mounted on studs 366 on the arms 362 to permit them to turn relatively to the arms and thus to 35 adjust themselves to the contour of the bottom of the shoe, such turning movements of the members being limited by engagement of the arms with shoulders 368 on the members. Between the two arms 362 is a spring 370 which tends to 40 swing the arms apart about the pins 360, such swinging movements of the arms being limited by a bolt 372 which extends through the spring and the arms and has thereon a nut 374 engaging one of the arms and adjustable to vary the spacing of the arms. To permit the holdown members 364 further to be positioned in proper relation to shoes of different sizes, the block 358 is 45 adjustable along the arm 356 on which it is mounted. Formed in this arm are a plurality of recesses 376 arranged to receive the end of a pin 378 slidably movable in the block 358 to retain the block in adjusted position. Fastened to this 50 pin is a plate 380 which extends across one end of

the block 358 and is provided with a lug 382 located at the opposite side of the block from the portion of the plate which is fastened to the pin 378 and normally spaced from that side of the block. In engagement with this lug is a spring 384 mounted in a recess in the block. Accordingly, the pin 378 may be withdrawn from any one of the recesses 376 by pressing against the lug 382 when it is desired to adjust the holdown members lengthwise of the shoe.

The hub 354 of the arm 356 is connected by a tongue 386 to the hub of an arm 388 which can turn about the rod 352, this arm being connected to a link 390. This link corresponds to the link 756 shown in Letters Patent No. 1,843,232 as a part of the means therein described for moving a shank holdown into and out of engagement with the insole, and it is operated by mechanism not herein shown but of the same character as the mechanism provided for operating the link 756. Accordingly, when the carrier 72 is moved downwardly to cause the heel presser foot 50 to impart downward movement to the last and shoe, the link 390 is moved toward the left, as the parts are viewed in Fig. 9, and swings the arm 356 about the rod 352 to move the holdown members 364 downwardly into engagement with the insole. As the wipers 88 wipe the upper inwardly over the insole their pressure against the holdown members 364 causes these members and the arms 362 to swing inwardly against the resistance of the spring 370, the margin of the upper being clamped between the wipers and the members 364 during a portion of the overwiping operation to increase the effectiveness of the wipers in wiping the upper tightly over the insole. Near the end of the inward movements of the wipers the holdown members 364 are swung reversely out of engagement with the shoe by the mechanism which controls the link 390.

The manner of operation of the machine, in so far as it is of interest with reference to the present invention, will now be briefly summarized. The operator mounts the shoe and last on the heel pin 14 and the toe rest 2 and then causes the heel band 18 to move into clamping relation to the heel end of the shoe by pressing on the plunger 20. He then spreads the margin of the toe end of the upper outwardly over the jaw 38 of the toe-end gripper and by depression of the treadle which operates the lever 40 moves the jaw 36 downwardly to grip the margin of the upper against the jaw 38, the jaw 36 being retained in upper-gripping position by engagement of the lug 46 with the latch 44. Thereafter the operator again presses on the plunger 20 to release the opposite side-lasting mechanisms and thus cause them to be moved by the springs 138 into positions determined by engagement of their bumpers 100 with the sides of the shoe. After the side-lasting mechanisms have received these positioning movements the operator positions the margin of the upper properly between the open jaws of their grippers 86, if it is not already so positioned, and then swings the arm 52 forwardly to actuate the clutch and thus start the power operation of the machine. In response to the clutch-actuating movement of this arm the valve 230 is closed, and by reason of the resulting pressure of the operating fluid delivered by the pump 212 the jaws 190 of the side grippers are moved into positions to grip the margin of the upper against the cooperating jaws 188.

Immediately after the starting of the machine the last and shoe are forced downwardly with the

work support 6 and the toe rest 2 by the action of the toe presser foot 48 and the heel presser foot 50 on the bottom of the shoe, and the holdown members 364 are swung downwardly into engagement with the opposite side margins of the insole. In response to the downward movement of the last the upper is pulled lengthwise of the last by the toe-end gripper and the opposite side grippers, and the side-lasting mechanisms are also moved a short distance lengthwise of the last toward its heel end to cause their grippers to pull the upper in that direction, this movement of the side-lasting mechanisms resulting from the downward movement of the work support 6. Thereafter the wipers 88 of the side-lasting mechanisms are operated to wipe the margin of the upper inwardly over the insole by the action of the cam 166 on the lever 134, and in response to the movement of this lever the bar 254 is released from the arm 252 and the valve 230 is opened to cause the grippers 86 to release the upper just as the wipers 88 begin to wipe it inwardly over the insole. The holdown members 364 are forced inwardly over the insole by these wipers, the margin of the upper being clamped between these members and the wipers to insure that the upper will be wiped tightly inward over the insole. Near the end of the inward movements of the wipers 88 the holdown members are swung upwardly away from the insole. After the wipers 88 have completed their inward movements they are retracted from over the shoe and the side-lasting mechanisms are returned to their outermost positions by reverse movement of the lever 134. The toe wipers 24 are then advanced and closed to wipe the margin of the toe end of the upper inwardly over the insole, these wipers being long enough to overlap portions of the margin of the upper previously wiped in by the side wipers 88. Just as the toe wipers start to wipe the upper over the insole the jaw 36 of the toe-end gripper is released by the lug 46 to permit it to return to starting position. After the toe wipers have operated on the upper in the manner more fully disclosed in Letters Patent No. 2,181,896, these wipers and other parts not already in their starting positions are returned to such positions, the shoe being removed from its support by automatic shoe-removing mechanism with which machines of the illustrated type are commonly provided. It will be understood that the side-lasting mechanisms are returned to their initial positions lengthwise of the shoe by the spring 318 when permitted by the return of the shoe support 6, and that the arm 252 also resumes automatically its initial position relatively to the valve-controlling bar 254.

Having described the invention, what I claim as new and desire to secure by Letters Patent of the United States is:

1. In a machine for shaping uppers over lasts, means for gripping the margin of an upper on a last, power-operated means for effecting relative movement of said upper-gripping means and the last to pull the upper, a clutch through which said power-operated means is operated, a starting member movable by the operator to actuate said clutch, and fluid-operated means operative independently of said clutch but controlled by said starting member for closing said upper-gripping means on the upper.

2. In a machine for shaping uppers over lasts, means for gripping the margin of an upper on a last, power-operated means for effecting relative

movement of said upper-gripping means and the last to pull the upper, a clutch through which said power-operated means is operated, a starting member movable by the operator to actuate said clutch, fluid-operated means operative independently of said clutch for closing said upper-gripping means on the upper, a valve for rendering said fluid-operated means effective thus to close the upper-gripping means, and means for operating said valve in response to the movement of said starting member.

3. In a machine for shaping uppers over lasts, means for gripping the margin of an upper on a last, power-operated means for moving the last heightwise relatively to said upper-gripping means to pull the upper, said power-operated means including a member movable by the operator from an idle position to a position opposite the bottom of the last, a clutch arranged to be actuated by the movement of said member and through which said power-operated means is operated, and fluid-operated means operative independently of said clutch but controlled by said member for closing said upper-gripping means on the upper.

4. In a machine for shaping uppers over lasts, means for gripping the margin of an upper on a last, power-operated means for moving the last heightwise relatively to said upper-gripping means to pull the upper, said power-operated means including a member movable by the operator from an idle position to a position opposite the bottom of the last, a clutch arranged to be actuated by the movement of said member and through which said power-operated means is operated, fluid-operated means operative independently of said clutch for closing said upper-gripping means on the upper, a valve for rendering said fluid-operated means effective thus to close the upper-gripping means, and means for operating said valve by the movement of said member.

5. In a machine for shaping uppers over lasts, means for gripping the margin of an upper on a last, power-operated means for effecting relative movement of said under-gripping means and the last to pull the upper, a clutch through which said power-operated means is operated, a starting member movable by the operator to actuate said clutch, fluid-operated means operative independently of said clutch but controlled by said starting member for closing said upper-gripping means on the upper, and mechanism operated by said clutch for also controlling said fluid-operated means to cause the upper-gripping means to release the upper.

6. In a machine for shaping uppers over lasts, means for gripping the margin of an upper on a last, power-operated means for effecting relative movement of said upper-gripping means and the last to pull the upper, a clutch through which said power-operated means is operated, a starting member movable by the operator to actuate said clutch, fluid-operated means operative independently of said clutch for closing said upper-gripping means on the upper, a valve movable to render said fluid-operated means effective thus to close the upper-gripping means, means for thus moving said valve by the movement of said starting member, and mechanism operated by said clutch for also controlling said valve to cause the upper-gripping means to release the upper.

7. In a machine for shaping uppers over lasts, means for gripping the margin of an upper on a last, power-operated means for effecting relative movement of said upper-gripping means and the

last to pull the upper, a clutch through which said power-operated means is operated, a starting member movable by the operator to actuate said clutch, fluid-operated means for closing said upper-gripping means on the upper, a reservoir for operating fluid, a continuously operated pump for delivering fluid from said reservoir, said pump being in continuous communication with said fluid-operated means, a valve normally permitting fluid to return from the pump to the reservoir to maintain the fluid delivered by the pump at substantially atmospheric pressure, and means controlled by said starting member for closing said valve to cause the pump to develop pressure sufficient to close said upper-gripping means.

8. In a machine for shaping uppers over lasts, means for gripping the margin of an upper on a last, power-operated means for effecting relative movement of said upper-gripping means and the last to pull the upper, a clutch through which said power-operated means is operated, a starting member movable by the operator to actuate said clutch, fluid-operated means for closing said upper-gripping means on the upper, a reservoir for operating fluid, a continuously operated pump for delivering fluid from said reservoir, said pump being in continuous communication with said fluid-operated means, a valve normally permitting fluid to return from the pump to the reservoir to maintain the fluid delivered by the pump at substantially atmospheric pressure, means for closing said valve in response to the movement of said starting member to cause the pump to develop pressure sufficient to close said upper-gripping means, and mechanism controlled by said clutch for again opening said valve to cause the upper-gripping means to release the upper.

9. In a machine for shaping uppers over lasts, grippers for gripping the margin of an upper respectively at opposite sides of a last, each of said grippers comprising a pair of upper-gripping jaws relatively movable to grip the upper and a cylinder-and-piston device for effecting such relative movement of the jaws by fluid pressure, power-operated means for effecting relative movement of said grippers and the last to pull the upper, a clutch through which said power-operated means is operated, a starting member movable by the operator to actuate said clutch, a source of supply of operating fluid, and valve means controlled by said starting member for rendering fluid from said source effective on said cylinder-and-piston devices to cause the jaws to grip the upper.

10. In a machine for shaping uppers over lasts, grippers for gripping the margin of an upper respectively at opposite sides of a last, each of said grippers comprising a pair of upper-gripping jaws relatively movable to grip the upper and a cylinder-and-piston device for effecting such relative movement of the jaws by fluid pressure, power-operated means for effecting relative movement of said grippers and the last to pull the upper, a clutch through which said power-operated means is operated, a starting member movable by the operator to actuate said clutch, a reservoir for operating fluid, a continuously operated pump for delivering fluid from said reservoir, said pump being in continuous communication with said cylinder-and-piston devices, a valve normally permitting fluid to return from the pump to said reservoir to maintain the fluid delivered by the pump at substantially atmospheric pressure, and means for closing said

valve in response to the movement of said starting member to cause the pump to develop pressure sufficient to close the gripper jaws on the upper.

11. In a machine for shaping uppers over lasts, means for gripping the margin of an upper on a last, fluid-operated means for closing said upper-gripping means on the upper, a reservoir for operating fluid, a continuously operated pump for delivering fluid from said reservoir, a valve 10 normally permitting fluid to return from the pump to the reservoir to maintain the fluid delivered by the pump at substantially atmospheric pressure, and means for closing said valve to cause the pump to develop greater pressure, said fluid-operated means being in continuous communication with said pump to cause the upper-gripping means to close on the upper in response to the closing of said valve.

12. In a machine for shaping uppers over lasts, 20 grippers for gripping the margin of an upper respectively at opposite sides of a last, each of said grippers comprising a pair of upper-gripping jaws relatively movable to grip the upper and a cylinder-and-piston device for effecting such relative movement of the jaws by fluid pressure, a reservoir for operating fluid, a continuously operated pump for delivering fluid from said reservoir, a valve normally permitting fluid to return from the pump to said reservoir to maintain the 30 fluid delivered by the pump at substantially atmospheric pressure, and means for closing said valve to cause the pump to develop greater pressure, said cylinder-and-piston devices being in continuous communication with said pump to cause them to operate in response to the closing of said valve.

13. In a machine for shaping uppers over lasts, opposite side-lasting mechanisms movable widthwise of a last into positions to operate upon an upper on the last and each comprising a gripper for gripping the margin of the upper and pulling the upper and a wiper for thereafter wiping the margin of the upper inwardly over the bottom of the last, each of said grippers comprising a pair of upper-gripping jaws and a cylinder-and-piston device for effecting relative movement of the jaws by fluid pressure to grip the upper, a source of supply of operating fluid, and means for rendering the operating fluid effective to operate the cylinder-and-piston devices after the side-lasting mechanisms have received their positioning movements widthwise of the last.

14. In a machine for shaping uppers over lasts, opposite side-lasting mechanisms movable widthwise of a last into positions to operate upon an upper on the last and each comprising a gripper for gripping the margin of the upper and pulling the upper and a wiper for thereafter wiping the margin of the upper inwardly over the bottom of the last, each of said grippers comprising a pair of upper-gripping jaws and a cylinder-and-piston device for effecting relative movement of the jaws by fluid pressure to grip the upper, and flexible conduits connected to said cylinder-and-piston devices for conducting operating fluid thereto while permitting movements of said side-lasting mechanisms toward and from the last.

15. In a machine for shaping uppers over lasts, a gripper for gripping the margin of an upper on a last and for pulling the upper, said gripper comprising a cylinder arranged to extend generally in a direction transverse to the height of the last, a pair of upper-gripping jaws supported on said cylinder in a location substantially oppo-

site one end thereof and arranged to extend generally heightwise of the last, and a piston in said cylinder, said cylinder and piston being relatively movable by pressure of operating fluid admitted to the cylinder to cause said jaws to grip the margin of the upper.

16. In a machine for shaping uppers over lasts, a gripper for gripping the margin of an upper on a last and for pulling the upper, said gripper comprising a cylinder arranged to extend generally in a direction transverse to the height of the last, an upper-gripping jaw fast on said cylinder at one end thereof and arranged to extend generally heightwise of the last, a co-operating jaw mounted to swing toward and from said first-named jaw, a piston in said cylinder, a rod connecting said piston to said swinging jaw for swinging it toward the other jaw by movement of the piston in response to pressure of operating fluid admitted to the cylinder, and a spring for imparting return movement to the piston.

17. In a machine for shaping uppers over lasts, 25 a gripper for gripping the margin of an upper on a last and for pulling the upper, said gripper comprising a cylinder arranged to extend generally in a direction transverse to the height of the last, a pair of upper-gripping jaws supported on said cylinder substantially opposite one end thereof, a piston in said cylinder for effecting relative upper-gripping movement of said jaws in response to pressure of operating fluid admitted to the cylinder, the cylinder being mounted for swinging movement heightwise of the last 35 in response to resistance of the upper to the force of the pull applied thereto, and a spring against the resistance of which the cylinder is thus movable.

18. In a machine for shaping uppers over lasts, 40 grippers for gripping the margin of an upper respectively at opposite sides of a last in locations where the edge of the shoe bottom curves inward heelwardly of the ball line, means for effecting relative movement of said grippers and the last to cause the grippers to pull the upper heightwise of the last, and additional means for imparting to the grippers in the course of said relative movement a movement lengthwise of the last toward its heel end to cause them to pull the upper also in that direction.

19. In a machine for shaping uppers over lasts, 45 grippers for gripping the margin of an upper respectively at opposite sides of a last in locations where the edge of the shoe bottom curves inward heelwardly of the ball line, means for moving the last relatively to the grippers to cause the grippers to pull the upper heightwise of the last, and mechanism for moving the grippers lengthwise of the last toward its heel end to cause them to pull the upper also in that direction.

20. In a machine for shaping uppers over lasts, 50 grippers for gripping the margin of an upper respectively at opposite sides of a last in locations where the edge of the shoe bottom curves inward heelwardly of the ball line, means for moving the last relatively to the grippers to cause the grippers to pull the upper heightwise of the last, and mechanism for imparting to the grippers in response to such movement of the last movement lengthwise of the last toward its heel end to cause them to pull the upper also in that direction.

21. In a machine for shaping uppers over 55 lasts, grippers for gripping the margin of an

upper respectively at opposite sides of a last in locations where the edge of the shoe bottom curves inward heelwardly of the ball line, means for moving the last relatively to the grippers to cause the grippers to pull the upper heightwise of the last, a work support arranged to partake of such movement of the last, mechanism carried by said work support for imparting to the grippers movement lengthwise of the last toward its heel end to cause them to pull the upper also in that direction, and means relatively to which the work support is thus movable for operating said mechanism in response to the movement of the work support.

22. In a machine for shaping uppers over lasts, grippers for gripping the margin of an upper respectively at opposite sides of a last in locations where the edge of the shoe bottom curves inward heelwardly of the ball line, means for moving the last relatively to the grippers to cause the grippers to pull the upper heightwise of the last, a work support arranged to partake of such movement of the last, mechanism including a lever carried by said work support for imparting to the grippers movement lengthwise of the last toward its heel end to cause them to pull the upper also in that direction, and a member into engagement with which said lever is carried by the work support for operating the lever in response to further movement of said support. 25

23. In a machine for shaping uppers over lasts, grippers for gripping the margin of an upper respectively at opposite sides of a last in locations where the edge of the shoe bottom curves inward heelwardly of the ball line, means for moving the last relatively to the grippers to cause the grippers to pull the upper heightwise of the last, a work support arranged to partake of such movement of the last, a member on said work support for imparting to the grippers movement lengthwise of the last toward its heel end to cause them to pull the upper also in that direction, and another member into engagement with which said first-named member is carried by the work support for operating the first-named member in response to further movement of said support, said members being relatively adjustable to vary the initial space between them and thus to vary the amount of movement lengthwise of the last imparted to the 50 grippers.

24. In a machine for shaping uppers over lasts, the combination with means for laying the margin of an upper inwardly over an insole on a last at the opposite sides of the last, of 5 hold-down members arranged to press the opposite side marginal portions of the insole upon the bottom of the last, said members being movable inwardly over the insole each about an axis extending heightwise of the last in response to pressure of said overlaying means thereon in laying the margin of the upper over the insole, and a support for said members movable about an axis extending widthwise of the last to carry them into engagement with the insole.
- 10 25. In a machine for shaping uppers over lasts, the combination with means for laying the margin of an upper inwardly over an insole on a last at the opposite sides of the last, of hold-down members arranged to press the opposite side marginal portions of the insole upon the bottom of the last, said members being movable inwardly over the insole each about an axis extending heightwise of the last in response to pressure of said overlaying means thereon in laying the margin of the upper over the insole, and an arm supporting said members and mounted for swinging movement heightwise of the last to carry the members into engagement with the insole, the members being adjustable relatively to said arm to vary their positions 20 lengthwise of the last.

- 30 26. In a machine for shaping uppers over lasts, the combination with means for laying the margin of an upper inwardly over an insole on a last at the opposite sides of the last, of hold-down members arranged to press the opposite side marginal portions of the insole upon the bottom of the last, arms supporting said members and mounted for swinging movements 35 inwardly over the insole about axes extending heightwise of the last in response to pressure of the overlaying means on the members in laying the margin of the upper over the insole, spring means against the resistance of which the arms are thus movable, a block on which the arms 40 are thus mounted, and an arm supporting said block and mounted for swinging movement heightwise of the last to carry the hold-down members into engagement with the insole.
- 45

BERNHARDT JORGENSEN.

CERTIFICATE OF CORRECTION.

Patent No. 2,244,067.

June 3, 1941.

BERNHARDT JORGENSEN.

It is hereby certified that error appears in the printed specification of the above numbered patent requiring correction as follows: Page 7, first column, line 45, claim 5, for the word "under" read --upper--; page 8, second column, line 7, claim 16, for "upers" read --uppers--; and that the said Letters Patent should be read with this correction therein that the same may conform to the record of the case in the Patent Office.

Signed and sealed this 15th day of July, A. D. 1941.

Seal:

Henry Van Arsdale,
Acting Commissioner of Patents.
